ARTIFICIAL FISHING LURE SPINNER BLADE

William O. Williams, Jr., 1309 Lynhurst Drive,
Gastonia, N.C. 28053

Filed May 10, 1974, Ser. No. 468,819

Term of patent 14 years

Int. Cl. D22—05

U.S. Cl. D22—29

FIG. 1 is a perspective view of an artificial fishing lure spinner blade of the present invention;

FIG. 2 is a side elevation view of the artificial fishing lure spinner blade of the present invention;

FIG. 3 is a side elevation view as viewed from the side opposite the side illustrated in FIG. 2;

FIG. 4 is a front end elevation view of the artificial fishing lure spinner blade of the present invention;

FIG. 5 is a rear end elevation view of the artificial fishing lure spinner blade of the present invention; and

FIG. 6 is a top plan view of the artificial fishing lure spinner blade of the present invention.

The surface configuration of one side of the artificial fishing lure spinner blade of the present invention is formed by a plurality of indentations, such indentations being represented in the drawings by closed poly-sided

figures dispersed throughout the surface on one side of the illustrated artificial fishing lure spinner blade.

I claim:

The ornamental design for an artificial fishing lure spinner blade, as shown and described.
